MEANS FOR COMPILING AND JUSTIFYING
COLUMNS OF WRITTEN MATTERVictor C. Heybourne, Tonawanda, N. Y., assignor
to Remington Rand Inc., New York, N. Y., a
corporation of Delaware

Application April 20, 1950, Serial No. 157,056

5 Claims. (Cl. 95—85)

1

The present invention relates to visible index cards of the type which have hitherto been used for many years in connection with indexing systems and which have fixing lugs cut out from the card to be distorted rearwardly for engagement behind laterally directed marginal flange portions of a runway. The cards are thus slidably carried by the runway in nested overlapping relationship and the lugs are so placed that those of each card cooperate with the bottom edge of its cooperating immediate under card to determine the degree of overlap of the nested cards. In general, the overlap is such that a narrow top margin strip of each under card, sufficient to accommodate one or perhaps a few lines of written matter, is exposed beyond the top edge of the card which overlays it. The runways are usually mounted on panels or other carriers and, when the cards are wide, two or more runways may be provided in spaced parallel relationship on each panel.

Examples of such cards, the mounting means and the operating technique are described, for example, in the prior U. S. Patents numbered: 1,048,056, 1,048,057 and 1,048,058 patented December 24, 1912; 1,628,124 patented May 10, 1927, and 1,675,331 patented July 3, 1928.

In recent years cards of the class above described have been found to have a very useful embodiment in the reproduction of printed matter by the offset and letterpress methods from plates obtained by photographing a panel built up line by line from typewritten cards. Such an embodiment is described in the copending application of Charles M. Ehnes, Serial No. 81,124 filed March 12, 1949, and that of Donald A. Gunn, Serial No. 129,826 filed November 28, 1949, now Patent No. 2,635,607 of April 21, 1953.

The procedure described in the aforesaid applications lends itself exceptionally well to the compilation of parts catalogs, schedules, telephone directories, etc., and lists of statistical records, the contents of which may require to be varied from time to time in respect of individual items to incorporate changes or corrections and to accommodate newly inserted matter or substituted matter without interfering with the general format of the various panel layouts. In such embodiments it is sometimes required, in the interest of general neatness that the column heights of the written matter of the various columns or pages are required to be all the same. For example, in building up columns for a telephone directory, the top line of the various adjacent columns will be properly aligned trans-

2

versely across the page but the bottom lines will not necessarily be so. The finished result is then lacking in neatness and general tidiness, and many of the telephone companies insist that the columns be justified to avoid it.

The invention is essentially concerned with a method of, and with the provision of means for justifying columns of cards of the class described and it will now be described by way of example, with reference to the accompanying diagrammatic drawings in which:

Fig. 1 is a plan view looking on the face of a card of a well known type of the class described, but adapted according to the invention, for use with an elevating strip for justifying purposes.

Fig. 2 is a plan view fragmentarily showing a runway with three cards engaged on it in their normal nested relationship without justifying.

Fig. 3 is a plan view looking on the face of an elevating strip according to the invention.

Fig. 4 is a plan view looking on the face of a card like that of Fig. 1 with the elevating strip engaged therewith to provide a justifying stage in accordance with the present invention.

Fig. 5 is a view corresponding to Fig. 2 but showing the effect of a single stage of justifying.

Fig. 6 is a plan view of a modified form of justifying assembly operating in a manner similar to that of Fig. 3.

Fig. 7 is a plan view of a nested pair of adjacent cards of a further modified type adapted for justifying by the provision of alternative intermembering means.

The card generally indicated by the reference numeral 10 in Fig. 1 is of rectangular form having an upper edge 11, a lower edge 12, and side edges 13 and 14, respectively. Laterally spaced die-cuts 15 are provided to define the intermembering tongues 16 which can be flexed to engage under the laterally directed flanges of a runway so that the nested cards extend over the face of the runway, as seen in Fig. 2; the whole technique being in accordance with that described in the aforesaid prior patents and applications. The cards are also usually provided with a faintly ruled pale blue line 17 which serves as a guide for typewriting so that a line of typewritten matter can be accurately placed in the marginal strip 18 across the top of the card. The line 17 is such that whereas it is sufficiently apparent to serve as a line guide for typing, it will not normally be reproduced when a card assembly is photographed for reproduction, for not only is it so faint that there is not sufficient contrast between the color of the line and the color

of the card to be reproduced by any normal photographic process, but also it is generally intended that in a normally nested assembly of cards, the position of the typing guide line 17 coincides with, and is therefore obscured by, the upper edge of the overlying adjacent card.

It will be noted that the lower extremities of the die-cuts define spaced straight horizontal portions 19 extending transversely across the card, which portions 19 cooperate with the lower edge of a cooperating adjacent under card. Thus, as seen in Fig. 2, which shows an interengaged series of three cards on a short broken off portion of runway generally indicated by the reference numeral 20, the tongues of the card 10, which is the lowermost and outermost of the series, are not visible from the face of the assembly because they are engaged behind the laterally directed flanges 21 of the runway and, furthermore, because the immediately adjacent under card 10a, a lower part of which is visible through the die-cuts 15, is engaged between the back of the card 10 and the face of the runway. The lower part of the card 10a is thus visible through the die-cuts 15 with its lower edge 12a engaged against the straight horizontal portions 19, see Fig. 1, of the die-cuts to define the extent of exposure of the top marginal portion 18a. Location of the card 10a in the lateral sense is assured by the fact that its tongues (not seen in Fig. 2) are engaged under the flanges 21 with the straight vertical portions 22 (see Fig. 1) of the die-cuts accurately abutting the outside edges 23 of the runway flanges. The third card 10b, the lower edge 12b of which is just visible in Fig. 2 through the die-cuts 15, and each subsequent card of the series, is similarly located in relation to its immediately cooperating over card. It will thus be seen from Fig. 2 that the upper edges 11, 11a, and 11b of the respective cards 10, 10a and 10b are equally spaced and that the top marginal strips 18, 18a and 18b are therefore equal. The cards moreover, being slidably nested on the runways, can be separated longitudinally of the runways to permit the insertion of additional cards, or for substitution, and, when the final panel format has been achieved, the assembly is masked, as described for example in the aforesaid application of Ehnes, for photographing.

As so far described, the procedure is well known and the only difference which the cards, according to the present invention, have over the hitherto known cards is in the provision of means for justifying the height of columns on a runway or the matter of consecutive panels so that the top and bottom lines of adjacent columns or pages are accurately aligned in the finished reproduction. In that respect it will be appreciated that any discrepancy will manifest itself in the bottom line of a column or page being out of alignment with respect to the bottom line of its adjacent column or page to the extent of the height of the line of type or print plus a certain amount of the normal line spacing or, in other words, to an amount corresponding to the depth of exposure of the complete card top margin 18. There are some cases, for example, in a telephone directory where the last item at the bottom of the page happens to be a multiple line insertion which ought not to be broken up and continued on the next column or page in which the discrepancy may amount to a whole number multiple of top margin width 18. For convenience in description, however, let it be supposed

that two adjacent columns have been built up on their respective runways and it is found that if the top lines are properly aligned the respective bottom lines will be out of alignment to the extent of one full top margin 18. Any attempt to absorb that discrepancy by increasing the exposure of any single margin 18 will noticeably spoil the whole format of the page or column, but if, with proper justifying, the total discrepancy is taken up in several small integers at substantially equally spaced points throughout the length of the column or page, the effect will pass practically unnoticed in the finished reproduction.

It is with the means for justifying the card columns that the invention is essentially concerned, and such means will now be described.

Thus in Figs. 1 and 2 it will be noted that the card 10 is provided with a horizontally extending slot 25 in the center of the card between the die-cuts 15. The slot 25 is adapted and arranged for the reception of a tongue 26 extending from the top edge of the elevating strip 27 (see Fig. 3). The elevating strip 27 is of such depth that when the notch 26 is fully engaged in the slot 25 of the card as seen in Fig. 4, the bottom edge 28 of the elevating strip projects beyond the lower edge of the card so that when an elevating strip is inserted to provide a justifying stage, it is the bottom edge 28 of the elevating strip, and not the bottom edge 12 of the card, which engages the straight horizontal portions 19 of the die-cuts of the adjacent overlying card. The effect is that whenever an elevating strip is used the exposed upper marginal portion of the card with which it is associated is increased. Thus in Fig. 5 where an elevating strip is shown associated with the card 10b, the extent of exposure of the top marginal strip 18b is slightly greater than that of the strips 18 and 18a. The fact that the typing guide line 17b is exposed beyond the upper edge 12a of the card 10a is immaterial because, as hereinbefore stated, the type guide line is of such a nature that it will not be discernible in the finished reproduction.

It should be noted that the elevating strip 27 must be applied over the face of the card with which it is directly associated in order to leave the fixing lugs 16 free to be distorted rearwardly for engagement with the runway flanges 23.

It is a preferred feature of the invention that the elevating strips 27 should be somewhat wider than the cards in order that, as seen in Figs. 4 and 5, an edge portion 29 shall be visible beyond the edge of the card for signalling the position of the elevating strips. The edge portion 29 is also preferably ruled with a series of pale blue lines so that whereas it is apparent to the naked eye, it, like the typing guide line 17, will not be discernible in the finished reproduction.

It should be noted that the vertical offset provided at each justifying stage must always be of the order of a small fraction of each single line spacing margin 18 which has to be absorbed in justifying a column. Thus, with a normal exposure of each top margin to the extent of, for example $\frac{1}{2}$ ", a single line shortage in a column can be concealed by increasing the line spacing by insertion of elevating strips at five points spaced substantially equidistant throughout the length of the column (heightwise), the normal top margin exposure being increased at each of the five stages by $\frac{1}{2}$ ". A normal top margin exposure of $\frac{1}{6}$ " would, under similar circum-

stances, call for six justifying stages increasing top margin exposure at six points spaced substantially equidistantly throughout the length of the column.

The modified construction shown with reference to Fig. 6, operates in the same way as that already described with reference to Figs. 1 to 5, and the sole difference which the Fig. 6 construction presents over that already described, is that in the Fig. 6 construction the elevator strip 27' has a pair of tongues 26', each for engagement with a cooperating slot formed in the card 10'. That feature is useful in order to obtain more satisfactory alignment in the wider range of cards.

The further modified construction shown with reference to Fig. 7, provides for increasing exposure of a card top margin without necessitating employment of a separate elevating strip. To that end, the modified card 10'' of Fig. 7 has, in addition to the die-cuts 15'' with their straight horizontal and vertical portions 19'' and 22'', respectively, knife cuts 30 each spaced between its adjacent die-cut and corresponding lateral margin substantially as shown. The knife cuts each define a tongue portion 31 which can be bent out of the plane of the card about a line joining the lower extremities of the lateral portions of the knife cuts to provide an alternative location for the lower edge of a cooperating under card different from that provided by the straight horizontal portions 19. Thus, in normal use, the straight horizontal portions 19'' are engaged by the lower edge of a cooperating under card to define a standard exposure of card top margin, but when, as seen in Fig. 7, a justifying stage is required, the top marginal exposure of the immediately cooperating under card 10''' is increased by engaging the bottom edge of the under card 10''' with the hinge line of the tongues 31, which, being at a different height relative to that of the straight horizontal portions 19'', provides the appropriate variation of top marginal exposure.

It is to be understood that where the expression "a small fraction" has been used in relation to the difference in top margin exposure provided at each justifying stage, the fraction has unity as its numerator, and its denominator represents the number of times the justifying stages are required to be repeated, heightwise of a column, effectively to conceal each single line spacing to be absorbed in justifying the complete column. Thus, in the instances hereinbefore specified $\frac{1}{26}$ " represents $\frac{1}{5}$ " of the normal exposure for each top margin 18 and hence five justifying stages are required. Similarly $\frac{1}{36}$ " is $\frac{1}{6}$ " of a normal $\frac{1}{6}$ " top margin exposure and requires six justifying stages effectively to conceal each single line difference. In general a difference more than $\frac{1}{5}$ of the normal top margin line spacing exposure at each justifying stage is liable to be too conspicuous, and though, theoretically, the justifying stages could occur between each line, there is in practice a limit beyond which repetition of the justifying stages is useful and commercially practical. Thus not only does excessive repetition become tedious but also, it is apt to result in the fractional differences at each justifying stage becoming so impractically small that the cards would have to be manufactured and finished to a degree of accuracy which would be difficult to achieve for ordinary commercial use. The term "small fraction" may therefore be defined as between the limits $\frac{1}{5}$ to $\frac{1}{12}$.

In the claims:

1. In an index or file, a card retaining strip adapted to present a pair of outwardly directed flanges, a plurality of index cards slidably mounted thereon, each card being provided with a pair of inwardly directed tongues struck out of said card and extending inwardly from a marginal portion thereof, said tongues having inwardly directed tab portions for engagement beneath said flanges, each card having portions of said margin at the base of said tongues in a fixed relation to the adjacent edge of said card, said cards engaging in offset interengaged relation on said strip, said portions at the base of said tongues and said adjacent card edges offsetting adjacent cards in internested relation to expose the opposite margin of each card in visible index relation, the combination of means connected to one of said cards adjacent said tongues in offset relation to said portions at the base of said tongues, said means engaging the marginal portion of an adjacent card and spacing said one card and adjacent card a different amount in overlapped relation from that provided by said portions at the base of said tongues, said means being concealed by said cards in assembled relation and providing means for justifying the spacing of said cards on said strip.
2. Card column justifying means as set forth in claim 1 characterized by the fact that, for engaging an elevating strip with a card, the cards are transversely slotted for the reception of complementary tongue means extending from the upper edge of the elevating strips.
3. For column justifying of cards of the class described each having an upper edge, a lower edge, and lateral edges joining said upper and lower edges and including die-cuts having transverse portions accurately positioned relative to said lower edge for cooperation with the lower edge of an immediately adjacent under card to determine the normal extent to which the upper edge of an under card projects beyond the upper edge of an immediately overlying card when the cards are installed in their nested relationship; a justifying insert cooperatively engageable with an under card to mask the lower part of said under card and project beyond the lower edge and also beyond one lateral edge, whereby the lower edge of said justifying insert cooperates with said die-cut to achieve a greater than normal extent of exposure of the top edge of an under card beyond its immediate overlying neighbor, whereas the lateral projection of said justifying insert beyond the lateral edge indicates the position of said inserts lengthwise of a column.
4. A card of the class described having a top edge and a bottom edge parallel therewith, and primary cuts defining intermembering tongues bendable out of the plane of the card for intermembering cooperation with an adjacent under card, the lower extremities of said primary cuts being equidistant from said bottom edge to define, when said tongues are bent out of the plane of the card for intermembering with an adjacent under card, adjacent under card locating means for locating the bottom edge of a cooperating adjacent under card in spaced parallel relationship with respect to said bottom edge of said card and thereby to determine a normal degree of exposure of the top of said under card beyond said top edge of said card; said card also having supplementary cuts defining upwardly extending supplementary tongues, the lower extremities of which supplementary cuts serve, when said sup-

plementary tongues are bent out of the plane of the card, to provide adjacent under card alternative locating means spaced from said bottom edge of said card a distance different from the spacing of the lower extremities of said primary cuts from said lower edge of said card to the extent of a fractional part of said normal degree of exposure, whereby said normal degree of exposure of a cooperating adjacent under card can be varied for justifying the column height of a 10 series of nested cards.

5. In panels of cards of the class described built up columnwise of individual cards having intermembering means cooperative between each under card and its immediately underlying card 15 to dictate a predetermined normal exposure of a top marginal portion of each under card beyond the upper edge of its cooperating immediately underlying card corresponding to a predetermined desired normal line spacing, the method of adapting said individual cards for column justifying which consists in providing said cards with alternative intermembering means so offset from said

first mentioned intermembering means that when any pair of adjacent nested cards is intermembered by means of said alternative intermembering means a justifying stage is provided at which the normal top margin exposure is varied to the extent of a small fraction (as hereinbefore defined) of said normal line spacing exposure, whereby column justifying can be achieved by repeating the justifying step as many times in a column as may be required to raise said fraction to unity for each unit line space to be absorbed in justifying.
